John B. Brennan, INVENTOR
BY Victor J. Evans
ATTORNEY

UNITED STATES PATENT OFFICE

JOHN B. BRENNEN, OF ATLANTA, GEORGIA

COTTON-CLEANER BEATER SHAFT

Application filed January 21, 1929. Serial No. 334,000.

This invention relates to a beater shaft for cotton cleaners, the general object of the invention being to make the ends of the beaters on the shaft of corrugated form so that the beaters or blades will throw the cotton away from the shaft and its blades instead of having the cotton pass around with the blades as is the case with the flat blades now in use.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:—

Figure 1 is a perspective view of a cotton cleaner with front portions broken away to show the beater shaft.

Figure 2 is an end view of the shaft.

Figure 3 is an end view of one of the blades or beaters.

Figure 4 is a side view of one of the blades or beaters.

In the drawing, the letter A indicates the casing of the cleaner which is of ordinary or any desired construction, and the letter B indicates the beater shaft which is rotatably arranged in the casing in the usual manner. In carrying out my invention, I form the outer portion of each blade or beater 1 of the shaft with corrugations, as shown at 2, so that when these blades pass through the cotton, the corrugations tend to throw the cotton outwardly from the blade, whereas the flat blades, as now in use, tend to carry the cotton around with them, as the cotton clings to these flat blades.

Operating tests with this corrugated type of blade proved that the corrugated blade is much more efficient as an opening medium than the flat blade.

It is thought from the foregoing description that the advantages and novel features of the invention will be readily apparent.

It is to be understood that changes may be made in the construction and in the com-

bination and arrangement of the several parts, provided that such changes fall within the scope of the appended claim.

What I claim is:—

A beater shaft for a cotton cleaner having longitudinal rows of straight blades thereon, the outer end of each blade being corrugated, with the corrugations extending longitudinally of the blade and said corrugations giving the blade a zigzag shape in cross section.

JOHN B. BRENNEN.
